US00D935933S

(12) **United States Design Patent** (10) **Patent No.:** **US D935,933 S**
(45) **Date of Patent:** **** Nov. 16, 2021**

(54) **PAIR OF EARRINGS**

(71) Applicant: **Harry Winston SA**, Plan-les-Ouates (CH)

(72) Inventor: **Dominique Riviere**, New York, NY (US)

(73) Assignee: **Harry Winston SA**, Plan-les-Ouates (CH)

(**) Term: **15 Years**

(21) Appl. No.: **29/727,667**

(22) Filed: **Mar. 12, 2020**

(30) **Foreign Application Priority Data**

Sep. 30, 2019 (WO) WIPO87960

(51) **LOC (13) Cl.** **11-01**

(52) **U.S. Cl.**

USPC **D11/43**
